UNITED STATES PATENT OFFICE.

JONATHAN C. MELOON, OF PROVIDENCE, RHODE ISLAND, ASSIGNOR TO THE GENERAL FIRE EXTINGUISHER COMPANY, OF NEW YORK, N. Y., A CORPORATION OF NEW YORK.

ELECTRIC ATTACHMENT.

SPECIFICATION forming part of Letters Patent No. 708,155, dated September 2, 1902.
Application filed March 1, 1898. Serial No. 672,152. (No model.)

To all whom it may concern:

Be it known that I, JONATHAN C. MELOON, of the city and county of Providence and State of Rhode Island, have invented certain new and useful Improvements in Electric Attachments; and I do hereby declare the following specification, taken in connection with the accompanying drawings, forming a part of the same, to be a full, clear, and exact description thereof.

The invention relates to an attachment more especially designed for use in connection with the "dry-pipe" valves or alarm-valves for automatic fire-extinguisher systems, although it may be employed in other relations where it is desired to close an electric circuit by the action of a fluid-pressure upon a movable member or diaphragm.

The object of the invention is to provide a simple and efficient device for closing an electric circuit by the action of a fluid-pressure, which will be positive in action, not likely to get out of order or become defective in action, and which may be readily inspected and repaired. To this end the invention consists in the combinations and features set forth in the claims.

In the drawings, Figure 1 is a sectional elevation on line 1 1, Fig. 2; and Fig. 2 is an end elevation, the shield being shown in section.

The devices for closing the electrical circuit are mounted upon a plate 1, which is slightly dished at 2 upon its under surface. A flexible diaphragm 4 is clamped between the under face of the plate 1 and a second plate 5, which is dished upon its upper surface to form a pressure-chamber 6 below the diaphragm. An inlet to the chamber 6 is formed by an opening 7 through the plate 5, and this inlet may be connected by a pipe 8 with a valve or other devices in connection with which the attachment is to be used. A plunger or block 9 rests upon or is secured to the upper face of the diaphragm 4 and extends up through the plate 1. The block is provided with a flange 10, which plays in a recess in the under face of the plate 1 and retains the plunger in place. This block is formed of insulating material and carries a

bearing-piece 12 at its upper end, which engages a contact-blade 13, pivoted at one end to a binding-post 11. The free end of the contact-blade is arranged to pass between two spring-plates 15 upon a second binding-post 16. The binding-posts 11 and 16 are supported from a block 17, of insulating material, by means of studs 18 on the ends of said posts, which extend through said block and are engaged by nuts 19, located in recesses in said block. The block 17 is secured by screws 20 to an overhanging arm 21, extending laterally from a standard 22, rising from the plate 1. Electric conductors in the form of wires 23 and 24 have their ends passed through the binding-posts 11 and 16, respectively, and secured thereto, preferably, by soldering said wires in the posts. The wires are covered with insulating material and pass from the binding-posts between two blocks 25 26 of insulating material, the wires being coiled, as at 27, to provide slack wire between the blocks 25 and 26 and the binding-posts. The blocks 25 and 26 are drawn together to clamp the wires between them by means of screws 28, which pass through the blocks and into holes tapped in the plate 1. A spring 29 is interposed between the block 21 and the contact-blade 13 and serves to hold the bar in engagement with the bearing-piece 12. A shield 30 may be provided for covering the operative parts of the device and protecting them from dirt or accidental displacement, and this shield may be held in place by a screw 31.

In operation the conductors 23 and 24 are connected with the poles of an electric generator, and the device, the operation of which is to be controlled by fluid-pressure, is included in the circuit. The diaphragm 4 normally stands in the dotted-line position, and the contact-blade is out of engagement with the plates 15, the circuit, therefore, being open at this point. When a fluid under pressure is admitted to the chamber 6—as by the opening of a valve, for instance—the fluid acts to raise the diaphragm into the full-line position, thus lifting the contact-blade and closing the circuit. An electric current now passes

through the device to be operated—such as an electric alarm, for instance—and operates said device.

By supporting the binding-posts, as above described, from a block of insulating material the posts are perfectly insulated and there is no danger that the wires leading thereto will come into contact with the metallic parts and short-circuit the current and prematurely ring the alarm. Moreover, with this construction ready access may be had to the various parts, and they may be readily removed for repairs. By passing the conductors through clamping-blocks before they are connected with the binding-posts there is no danger that the contact between the conductors and the posts will be impaired by any accidental strain put upon the conductors outside the clamping-blocks.

20 What I claim as my invention, and desire to secure by Letters Patent, is—

1. The combination with a pressure-chamber, of a diaphragm therein, a plunger operated thereby, a block of insulating material, 25 binding-posts depending therefrom and supported thereby, an overhanging arm to which said block is secured, a contact-blade pivoted to one of said posts and engaged by said plun-

ger, and plates secured to the other post between which said blade passes. 30

2. The combination with two dished plates, a diaphragm clamped between said plates, an inlet through one plate, a plunger extending through the second plate and engaging the diaphragm, a standard projecting from the second plate, an arm extending laterally from said standard, a block of insulating material secured to the under face of said arm, binding-posts depending from said block, and a contact-blade engaged by said plunger for connecting said posts. 35

3. The combination with dished plates 1 and 5, of a diaphragm 2 clamped between said plates, an inlet 7 to the chamber 6 below the diaphragm, a standard 22 rising from plate 1, 45 an arm 21 extending laterally from said standard, a block 17 of insulating material secured to the under side of said arm, binding-posts 11 and 16 supported by said block, a contact-blade 13 pivoted to post 11, plates 15 carried 50 by post 16, and a plunger 9 engaging diaphragm 2 and contact-blade 13.
